UNITED STATES PATENT OFFICE.

RAYMOND R. FUDGE, OF FORT WORTH, TEXAS.

DESIGN FOR AN AUTOMOBILE GEAR-SHIFT-LEVER GRIP.

Application filed March 27, 1923. Serial No. 5,609. Term of patent 7 years.

To all whom it may concern:

Be it known that I, RAYMOND R. FUDGE, a citizen of the United States, residing at Fort Worth, in the county of Tarrant and State of Texas, have invented a new, original, and ornamental Design for Automobile Gear-Shift-Lever Grip, of which the following is a specification, reference being had to the accompanying drawing, forming part thereof.

The figure is a perspective view of an automobile gear shift lever grip, showing my new design.

I claim:

The ornamental design for an automobile gear shift lever grip, as shown.

RAYMOND R. FUDGE.
